UNITED STATES PATENT OFFICE

ERNEST P. PARSONS, OF CLEVELAND, OHIO; WILBUR M. BALDWIN, ADMINISTRATOR OF SAID ERNEST P. PARSONS, DECEASED, ASSIGNOR TO THE PARSONS & PARSONS COMPANY, OF CLEVELAND, OHIO

CELLULOID COLLAR

Application filed April 12, 1926. Serial No. 101,277.

My invention relates to an improvement in celluloid collars, and more particularly in celluloid collars having separate button-hole tabs of the same celluloid material permanently affixed to the collar band by cement and supplemental fastening means, such for example, as disclosed in Letters Patent No. 1,023,223 dated April 16, 1912, and granted to A. H. Parsons.

10 My present object is to provide an exceptionally secure and sightly means of attachment for the button-hole tabs, using composition rivets of diminutive proportions to fasten the celluloid tab to the celluloid collar band. The composition is or may be the same in color as the collar itself and it provides a rivet which may be very small in diameter, whereby an inconspicuous and neat union is effected. The strength of the union is surprising since the composition rivets are so small, and the material thereof being substantially the same in color as the collar stock the rivets present a very pleasing appearance which is highly desirable in this 20 class of wearing apparel. No metal being used in uniting the tabs to the collar band no corrosion or objectionable change in appearance occurs nor will an objectionable coating form on the rivets when the collars are carried in stock in moist climates or when worn and repeatedly exposed to the moisture and impurities exuding from the skin.

25 In the accompanying drawing, Fig. 1 is a perspective view of a celluloid collar embodying the present improvement. Fig. 2 is a sectional view of a portion of the collar on the line of riveted union for a tab. Fig. 3 is an inside view of one tab end of the collar, and Fig. 4 is a horizontal section thereof through the tab and a composition rivet. Fig. 5 is an inside view of one end of the collar body, and Fig. 6 a side view of a separate button-hole tab.

30 As exemplified herein, the invention com-

prises a folded collar in which the inner band 2 is of the same length and terminates approximately at the same point as the outer pliy or fold 3. Affixed to opposite ends of band 2 are separate button-hole tabs 4 which provide free flexing extensions for the band, and these tabs are permanently affixed to the band by cement and a plurality of rivets 5 made of a composition such as celluloid. The cemented union preferably involves only the 50 extreme inner end portion in the tab in register with similar openings 8 of the same diameter in the end part of the band. Openings 8 are reamed more or less remotely from the vertical end edge 9 of the band, and the 55 rivets 5, which are solid and of smaller diameter, are inserted in the registering openings and upset at their opposite ends to cause the shank of the rivet to fit tightly within the opening and to clamp the tab 60 tightly to the band. When the tab is secured in its proper position upon the band by means of the cement and the composition rivets the upper straight edge 10 of the tab 65 is contiguous to or in contact with the folded 70 corner 11 of the collar. Button-hole 12 in the tab is placed relatively near the end edge 9 of the band and therefore the cemented and riveted union is remotely related to the end edge 9 which permits the tab to flex apart 75 from the band opposite edge 9 intermediate button-hole 12 and the rivets 5. The collar body and separate tabs and the rivets may all be made of the same celluloid composition of matter, or of substantially similar 80 substances, thereby providing a water proof collar in which the riveted connection is of the same color and has the same cleansing and water proof characteristics and properties as the remainder of the collar.

What I claim, is:

A celluloid collar of the folded type, having a band which is perforated at different elevations at its opposite ends, separate buttonhole tabs, perforated to correspond with 90

the perforated ends of the band, said tabs being cemented at their perforated areas to said collar in such a position that the upper edge of each tab contacts with the corresponding folded edges of the collar, and a plural number of solid celluloid rivets inserted through said aligned perforations of said band and said tabs, the intermediate portion of each tab between its buttonhole and the rivets being free to flex apart from said band.

In testimony whereof I affix my signature.

ERNEST P. PARSONS.
